UNITED STATES PATENT OFFICE.

LINN BRADLEY, OF EAST ORANGE, NEW JERSEY, ASSIGNOR TO RESEARCH CORPORATION, OF NEW YORK, N. Y., A CORPORATION OF NEW YORK.

MECHANICAL RECTIFIER.

Application filed February 14, 1919. Serial No. 277,019.

To all whom it may concern:

Be it known that I, LINN BRADLEY, a citizen of the United States, residing at East Orange, in the county of Essex and State 5 of New Jersey, have invented certain new and useful Improvements in Mechanical Rectifiers, of which the following is a specification.

The present invention relates to mechanical rectifiers.

Mechanical rectifiers, especially those of the contact type, have the serious drawback that destructive arcing takes place because of the impossibility of always commutating 15 the current at the precise instant when the electromotive force is zero. This is especially the case in connection with load devices having a variable inductance or capacity.

Rectifiers are extensively used to convert high tension alternating current into unidirectional current to charge electric precipitators. An electric precipitator is, as is well known a leaky condenser of considerable capacity. Relatively slight disturbances in the precipitator chamber cause a disturbance of the phase relations between current and voltage, and a disturbance of the phase relations manifests itself by 25 sparking at the commutator or rectifier brushes. Sparking in turn adds to the disturbance in the treater chamber and so on, so that small disturbing causes may result in surges and oscillations which work havoc 30 in the treater chamber and at the rectifier apparatus.

In the past much trouble has resulted from charring of insulation due to the destructive sparking between adjoining segments or contacts on the rectifier disk, which segments have been made of rectangular shape.

It is the object of this invention to reduce destructive arcing as much as possible and 45 at the same time to cause the arcing to take place at a point on the rectifier where it cannot do any harm to the insulation or to the contacting surface.

The object, operation and result of the 50 invention will appear more clearly from detailed description in connection with the accompanying drawings, in which—

Fig. 1 is a side view of what I consider at present as the preferred embodiment of 5 the invention;

Fig. 2 is an end view thereof;

Fig. 3 is a view similar to Fig. 1 showing a slightly modified use of the invention; and

Figs. 4-9 show modifications of a detail.

In the drawing 1 represents a rectifier disk made in the usual manner of insulating material, such as micarta, glass or other well known substances. The disk is preferably made in two parts so as to permit separate assembly. To this end the two halves of the disk are provided with flanges 2 by means of which they may be clamped together upon the shaft 3. Spacers 4 may be used to afford a rigid connection without straining the material. These details are not material to the invention and may be modified or changed as desired.

Along the periphery of the disk are disposed contact segments 5 and 6 which are generally similar to the segments usually employed to establish by contact with stationary contact shoes 7, 8, 9 and 10 electrical connection between the source of current and the load device in the well known manner. Adjacent the trailing end of the segments 5 and 6 and spaced therefrom are auxiliary contact members 11 and 12 respectively. The segments and the auxiliary contact members have overhanging portions 5', 6', 11' and 12' respectively to define free spaces therebetween and the edge of the disk. In these spaces are disposed horn-gap devices 13 and 14 respectively. One horn of each device is connected to one of the segments and the other to the adjacent auxiliary contact member. The horn-gap devices are so positioned that the axis of each lies substantially at right angle to a radius of the disk passing through it. In other words, the horn-gaps have their axes in the direction of motion of the disk with the result that the relative velocity of the air passing through the gaps is substantially equal to the peripheral velocity of the disk.

The operation of the device so far described is obvious. The disk is rotated in the direction of the arrow. As the trailing end of the segments leaves the stationary shoe, the electromotive force, if it should have at that time a value considerably above zero, tends to maintain the current flow in the form of an arc. The arc is sustained in proportion to the value of the electromotive force. Since the horns of the horn-gap

mechanism are relatively close together, an arc is established therebetween when the distance between the trailing end of the segment and the stationary shoe becomes greater than the horn-gap. As the distance between the segment and the stationary shoe increases, the arc is entirely shifted to the horn-gap, where it is then quickly extinguished by the well-known horn-gap action hastened by the action of the air current rushing through the gap.

A second set of auxiliary contact members 15 and 16 together with a second set of horn-gap mechanisms 17 and 18 may be employed in addition to the previously described devices. In this case the horns of the horn gap mechanisms 13 and 14 may be put closer together and the horns of the horn-gap mechanisms 17 and 18 are brought still closer together.

By the arrangement described not only the arcing between the stationary contact shoe and the contact elements on the disk, but also between the adjacent contact elements on the disk is reduced and such arcing as cannot be avoided is shifted to a point away from the insulation and from the contacting surface.

In Fig. 4 is shown an S-shaped element 30 connected to one side of a contact element 31 on the disk and extending close to the preceding contact element 31' in such a way as to form a horn 32 defining a spark gap.

In Fig. 5 is shown a spark gap formed between two spheres 33 in the space between adjacent contact elements 34 and 34' away from the insulation.

Figs. 6 and 7 show spheres 35 supported on arms 36 extending away from the contact elements in lateral direction.

In Figs. 8 and 9 a horn-gap is formed by elements 37 attached to the sides of the overhanging shoulders 38.

It is understood that the number of auxiliary contact members need not be restricted to two. The number of such auxiliary elements and horn-gaps, the spacing of the latter and the position thereof may be varied according to judgment or particular requirements.

It is also understood that the length of the segments may be varied in accordance with the portion of the alternating current wave to be rectified.

In Fig. 1, I have shown the segments long enough to span the stationary contact shoes. However, I contemplate also the shortening of the segments to such an extent that commutation takes place with one or more of the horn-gaps in circuit as shown in Fig. 3. The segment 20 subtends an angle of less than 90° and therefore does not span the stationary contacts 21 and 22. In the position shown the current passes say from the

stationary contact shoe 21 through the segment 20, then through the horn-gap mechanism 23 to the auxiliary contact member, to contact shoe 22 and to the load device (not shown) while the return current coming from the load device passes through the stationary contact shoe 24 to the auxiliary contact member 25, then through the horn-gap mechanism 26 to the segment 27 and then to the source of current. Thus an air gap is initially introduced into the circuit and as soon as the stationary contact shoes leave the trailing end of the auxiliary contact members the second set of horn gap mechanisms 28 and 29 is introduced into the circuit.

I have further shown the air gap between two opposed segments to be of less resistance than the leakage path over the insulation; therefore a break-down will take place from conductor to conductor through the air in preference to leaking over the surface of the insulating material of which the disc is made. This eliminates possibility of leakage, sparking or arcing near the insulating material, producing a breakdown of the disc by shattering or by carbonization or otherwise. Also, the brushes always ride upon metal of the same kind to insure equal wear. The air gaps and number of segments and the total insulation between brushes is selected to fit any desired voltage. Actual contact is had when the bulk of load current flows and helps to eliminate oscillations etc. etc.

I claim:

1. In a mechanical-contact rectifier the combination of a stationary contact shoe, a rotary disk of insulating material and a metallic segment thereon adapted to contact with the stationary shoe, an auxiliary metallic contact member on the disk spaced from the segment, and means for defining between the segment and the auxiliary contact member at a point away from the contact surfaces thereof an air gap which is smaller than the distance between the segment and the auxiliary contact member at their contact surfaces.

2. In a mechanical-contact rectifier the combination of a stationary contact shoe, a rotary disk of insulating material and a metallic segment thereon adapted to contact with the stationary shoe, an auxiliary metallic contact member on the disk spaced from the segment, and means for defining between the segment and the auxiliary contact member at a point away from the edge of the disk an air gap which is smaller than the space between the segment and the auxiliary contact member near the periphery of the disk.

3. In a mechanical-contact rectifier the combination of a stationary contact shoe, a rotary disk of insulating material and a

metallic segment thereon adapted to contact with the stationary shoe, an auxiliary metallic contact member on the disk spaced from the segment, and means for defining 5 between the segment and the auxiliary contact member at a point away from the edge of the disk an air gap which is smaller than the space between the segment and the auxiliary contact member near the periphery of 10 the disk and extends substantially in a radial direction.

4. In a mechanical-contact rectifier the combination of a stationary contact shoe, a rotary disk of insulating material and a 15 metallic segment thereon adapted to contact with the stationary shoe, an auxiliary metallic contact member on the disk spaced from the segment, and means for defining between the segment and the auxiliary contact member at a point away from the contact surfaces thereof an air gap which is 20 smaller than the distance between the segment and the auxiliary contact member at their contact surfaces and extends substantially in a radial direction.

5. In a mechanical-contact rectifier, the combination of a stationary contact shoe, a rotary disk of insulating material and a metallic segment thereon adapted to contact 30 with the stationary shoe, an auxiliary metallic contact member on the disk spaced from the segment and a horn-gap mechanism intermediate the segment and the auxiliary contact member.

35 6. In a mechanical-contact rectifier, the combination of a stationary contact shoe, a rotary disk of insulating material and a metallic segment thereon adapted to contact with the stationary shoe, an auxiliary metallic contact member on the disk spaced from the segment, and a horn-gap mechanism intermediate the segment and the auxiliary member having one horn connected to the former and the other horn to the latter.

45 7. In a mechanical-contact rectifier, the combination of a stationary contact shoe, a rotary disk of insulating material and a metallic segment thereon adapted to contact with the stationary shoe, an auxiliary metallic contact member on the disk spaced from the segment, and a horn-gap mechanism intermediate the segment and the auxiliary member having one horn connected to the former and the other horn to the latter, the 50 axis of the horn gap mechanism lying substantially at right angles to a radius of the disk passing through it.

8. In a mechanical-contact rectifier, the combination of a stationary contact shoe, a 55 rotary disk of insulating material and a

metallic segment thereon adapted to contact with the stationary shoe, an auxiliary metallic contact member on the disk spaced from the segment, the said segment and auxiliary contact member having adjacent to each other 65 overhanging portions defining a free space therebetween and the edge of the disk.

9. In a mechanical-contact rectifier, the combination of a stationary contact shoe, a rotary disk of insulating material and a metallic segment thereon adapted to contact with the stationary shoe, an auxiliary metallic contact member on the disk spaced from the segment, the said segment and auxiliary contact member having adjacent each other 75 overhanging portions defining a free space therebetween and the edge of the disk, and means for defining between the segment and auxiliary contact member at a point away from the edge of the disk an air gap which 80 is smaller than the distance between the overhanging shoulders.

10. In a mechanical rectifier, the combination of stationary contact shoes, a rotary disk of insulating material, metallic segments thereon adapted to contact with the stationary shoes and auxiliary metallic contact members disposed in spaced relation along the periphery of the disk intermediate the said segments and air gap mechanism between and forming part of adjacent contact members.

11. In a mechanical rectifier, the combination of stationary contact shoes, a rotary disk of insulating material, metallic segments thereon adapted to contact with the stationary shoes, auxiliary metallic contact members disposed in spaced relation along the periphery of the disk intermediate the said segments and means for varying the electric resistance between the segments and the separate auxiliary contact members.

12. In a mechanical rectifier, the combination of stationary contact shoes, a rotary disk of insulating material, a plurality of metallic contact elements disposed in spaced relation along the periphery of the disk and adapted to contact with said shoes and means for preventing leakage adjacent the disk, said means comprising conducting elements connected with the separate contact elements for defining in the spaces between the contact elements and away from the disk air-gaps which are smaller than the 11 distances between the adjacent contact elements.

In testimony whereof, I affix my signature.

LINN BRADLEY.
